METHOD OF PREPARING PRINTING MEMBERS FOR USE

Walter T. Gollwitzer, Cleveland, Ohio, assignor, by mesne assignments, to Addressograph-Multigraph Corporation, Cleveland, Ohio, a corporation of Delaware

Application February 29, 1936, Serial No. 66,332

19 Claims. (Cl. 101—1)

This invention relates to a method and apparatus for preparing printing members for use in a series printing machine. More particularly, the present invention relates to an improved method and apparatus for mounting printing plates in suitable frames or holders.

The general object of the present invention is to provide an improved method for preparing a printing plate, for use in a series printing machine, such as an "Addressograph", where each plate is mounted in a frame, and the frame progresses through the machine to enable successive impression to be made from the plates, one at a time.

Printing systems utilizing individual printing plates carried by respective frames, are well known at the present time. Such systems often employ thousands of printing units (combined plates and frames), as, for instance, a system of addressing invoices to the subscribers by large public utility corporations.

One advantage of using printing units comprising printing plates removably mounted on individual frames, is that the printing plate may be manufactured economically, in contrast with the cost of manufacturing plates which are intended for use without frames. This economical advantage results from the fact that the plates may be made of comparatively light material, without regard to rigidity or strength, as they are supported by frames while in use. The frames act to protect the plates by absorbing the shocks imparted to the units during their progress through the printing mechanism, as well as while they are being transferred between the printing machine and suitable storage receptacles, while the printing plate itself is subjected only to the compressive stresses of the printing action.

Another advantage of the separable units is that the frames may be arranged to protect the printing surfaces or characters of the plate when the units are stacked one above another. The frame may be manufactured of a material more readily adapted for long use and more capable of withstanding hard wear than a printing plate, as the latter must be made of material which will permit the embossing of suitable printing characters thereon.

As a result, it has been found that where the plates are mounted on individual frames, the frames outlast several printing plates, and provide a system which may be economically maintained.

In systems using such printing devices, when

a plate becomes worn, or when the subscriber's address is changed or dropped from the mailing lists, it is desirable to remove the plates from the frames, abandon the plates and insert new plates on the old frames.

One of the difficulties encountered in the use of plates removably mounted on frames, is that the plates, after embossing and prior to their assembly on the frames, must be kept in a predetermined order; for instance, either numerically according to the subscriber number, or alphabetically. Lists are furnished to the operators of embossing machines to enable them to emboss the plates in the order in which they are to be used in the printing machine. It has been found, however, that these plates, which are made of comparatively thin metal, are difficult to maintain in proper sequence, between the period of embossing and their storage on frames. It is therefore a specific object of the present invention to provide a method and apparatus which will insure the retention of the plates in proper sequence, until they are positioned on their frames and retained in position thereon, so that they may not be readily dislodged.

Another object of the present invention is to provide an improved apparatus for mounting printing plates on frames or holders. The apparatus of the present invention may be considered as an improvement on the apparatus shown, described and claimed in my copending application for Letters Patent, Serial No. 733,709, filed July 5th, 1934.

Other objects of the present invention will be explained in the following description, reference being had to the accompanying drawings, in which I have illustrated a preferred form of mechanism, included within my invention, which may be used in carrying out my improved method. The novel features of the invention will be set forth in the claims.

Referring now to the drawings, Fig. 1 is a plan view of an address printing plate; Fig. 2 illustrates the plate of Fig. 1, after the first step of my improved method has been carried out, namely, the embossing of the plate; Fig. 3 illustrates the plate of Fig. 2, after the ends thereof have been notched; Fig. 4 is a plan view of the complete printing device, namely, the plate assembled on a frame or holder; Fig. 5 is a fragmentary perspective view of the printing device illustrating the manner of retaining the plate in position on the frame; Fig. 6 is a fragmentary section through the printing device, as indicated by the line 6—6 on Fig. 4; Fig. 7 is a plan view of a mechanism on Fig. 4;

for mounting printing plates on their frames; Fig. 8 is a fragmentary transverse section of the mechanism illustrated in Fig. 7, the plane of the section being indicated by the line 8—8 on Fig. 7; Fig. 9 is a transverse vertical section, through the mechanism as indicated by the line 9—9 on Fig. 7; Fig. 10 is a fragmentary section similar to Fig. 9, but illustrating certain parts in a different position.

10 Referring again to the drawings, and especially to Figs. 1, 3 and 4, the printing plate with which this invention is especially concerned, comprises a substantially rectangular-shaped, thin plate A, made of a material sufficiently soft to permit printing characters to be embossed thereon in the usual manner, yet sufficiently hard to permit repeated use of the plate as a printing device. I have found that metal alloys, such as zinc, aluminum or tin, are well adapted for such use.

20 A series of plates of the type illustrated in Fig. 1, are utilized to make printing devices for a complete list of address printing members. The operator takes the plates one by one and embosses them with printing characters B in the usual manner, such as, for instance, by an embossing machine of the type illustrated in Patent No. 1,831,103, issued to my assignee, Addressograph Company, November 10th, 1931.

25 After a plate has been embossed, the operator, by use of any suitable punch mechanism, forms notches C in opposite ends of the plate, as illustrated in Fig. 3. These notches C, as noted from Fig. 3, are dove-tailed, that is, entrance to the notch is restricted relative to any other dimension 30 of the notch parallel with the entrance and inwardly therefrom. The notches are located on opposite ends of the plate substantially midway between the side edges thereof.

30 My improved method includes the step of 40 stacking these plates, one above the other, in the order in which they are embossed, that is, the order in which they are to be used in the printing machine, and maintaining them in such stacked relationship by engaging at least one 45 notch of each plate and thereafter positioning each plate on an individual frame holder and retaining the plate in position on said holder by engagement of the notches of the plate by portions of their respective frames.

50 A suitable frame or holder on which the address or printing plate A is to be mounted for use in printing machines, is best illustrated in Figs. 4, 7 and 9. As there shown, the frame comprises a sheet-metal member D, preferably of a more 55 substantial material than the printing plate. This frame is provided with a curled-over lower edge 11, which, together with stamped up ears 12, form a slideway for the printing plate A, and a curled-over upper edge 13, which coacts with 60 stamped-up ears 14 to form a pocket in which an index card, such as indicated at E in Fig. 5, may be positioned, if desired.

65 The lower portion of the frame is provided with spring tongues 15, cut out of the body of the plate near each end thereof, each tongue having a raised lip 16, presenting abrupt shoulders 17 to engage the end of the printing plate A, and a gradually inclined central portion 18 connecting this raised lip with the body of the tongue and 70 adapted to occupy the notch C of the printing plate. The inclined central portion 18 provides abrupt shoulders 20 to engage the side walls of the notches C and thereby accurately locate the plate on the frame. This permits the use of a 75 plate, which fits loosely in the guideways 11 and

12 to enable the plate to be easily inserted on the frame. The raised portion 16 of the spring tongue is also connected with the body of the tongue 15 by extreme portions 19 set back from the abrupt shoulders 17.

15 The side edges of the frame D are reenforced with suitable ribs 22, formed by downwardly and then upwardly curled portions of the frame member. These ribs space the printing devices, one above the other, so that the printing characters 10 will not be damaged by contact with other devices. The ribs 20 also act to strengthen the printing device, and may be, contacted by suitable progressing means to progress the printing plate 15 in the printing machine, as is well known and described in various patents assigned to my assignee, Addressograph Company.

20 The frame above referred to is claimed in my Patent No. 2,030,865, issued February 18th, 1936, and assigned to my assignee, Addressograph Company, and is here set out so that my improved method and apparatus may be better understood.

25 The mechanism which I have shown to facilitate the mounting of the plates on the frames is an improvement on the mechanism shown in my prior application for Letters Patent, Serial No. 733,709, heretofore mentioned. Briefly, this mechanism comprises a base 30, carrying a magazine 31, adapted to receive a stack of frames or 30 holders, a second magazine 32 adapted to receive a stack of embossed plates A and retain them in such stacked relationship as will be hereinafter more fully described, and a receiving magazine 33 into which the assembled printing devices are 35 stacked by mechanism carried by the base.

35 Suitable feeding mechanism is provided to feed the frames one at a time from the magazine 31, while other mechanism feeds the plates one at a time from the magazine 32, and mounts them on the frames. The feeding mechanism may, if 40 desired, act to remove an old plate from the frames, as they are progressed from the magazine 31, if a frame carries such plate. Such a mechanism is described and claimed in my copending application, heretofore referred to, and hence will 45 not be illustrated or described in the present application.

45 As shown in Fig. 7, the base 30 is provided with a guideway 34, along which the frames are fed from the magazine 31 to the magazine 32. 50 The bottommost frame is fed from the stack carried in the magazine 31 in the usual manner by a pusher 35, reciprocably mounted in the guideway, and arranged to engage the bottommost frame D, and shove it into the position illustrated by the frame D1 in Fig. 7. At the same time the second surface 36 of this pusher engages the frame which previously lay in the position indicated by the frame D1, and shoves it into the magazine 33. The arrangement of the magazine 60 33 is such that the printing devices are automatically stacked therein, consequent upon the operation of the pusher. Such device may either be accomplished by gravity, that is, by the devices dropping one at a time to a magazine, which sets 65 below the guideway 34, or, if preferred, by suitable arrangement such as shown in my prior applications heretofore referred to, which raises the successive plates up and retains them in such position so that the plates may be slid one beneath the other, and thus stacked.

70 As illustrated in Fig. 7, the guideway 34 is mounted on pivots 38, so that it may be rocked, causing the frame D1 (Fig. 7) to be raised upwardly, and the tongues 15 thereof to be de- 75

pressed, relative to the frame, by lips 39 carried by the base 30. The depression of the tongues 15 enables a printing plate A to be shoved from the magazine 32, across the depressed right-hand tongue 15 into position on the frame, whereupon the guideway is lowered, releasing the spring tongue 15 of the frame. The feeding mechanism thereafter functions to eject such combined frame and plate, shoving it into the 10 magazine 38 and position a new frame to receive a plate.

The feeding of the frames is accomplished by the rotation of a hand-wheel 40 by the operator. This hand-wheel, as shown in Fig. 9, is connected 15 by bevelled gearing 41, with a vertically extending shaft 42, which carries at its upper end an arm 43, provided with a roller 45. This roller engages a slot in a pivoted lever 44, which is provided, as shown in Fig. 7, with an arm 46, connected by a link 47, with a lever 48. The lever 48 is pivoted as at 49 to the base 30, and is provided at its outermost edge with a slot 50, the walls of which engage a ball 51, secured, as indicated at Fig. 10, to the pusher 35, causing the latter to be reciprocated in the guideway 34, thereby feeding the frames consequent upon the 20 operation of the handwheel 40.

The feeding mechanism is so arranged that the bottommost plate A is fed from the stack 30 carried in the magazine 32, and shoved onto the frame which occupies the position indicated by the frame D1, while the frame feeding pusher 35 is on its return stroke, thus forming a complete printing device. As shown in Figs. 9 and 10, the 35 plate feed mechanism comprises a pusher 52, secured to a bar 54, mounted in suitable guideways in the base 30 for reciprocation in a direction transverse to the frame guideway 34. The pusher 52 is provided with an abrupt edge 55 arranged 40 to engage the right-hand end of the bottommost plate A in the magazine 32 and shove it to the left (Fig. 7) into position on the frame D1.

The plate feed bar 54 is operated by the lever 44 heretofore described. As indicated in Figs. 9 45 and 10, this lever 44 is provided with a slot 60, the walls of which engage a roller 61 mounted on a stud 62 carried by the feed bar 54. Therefore, consequent upon the rotation of the hand-wheel, heretofore described, the plate-feeding 50 mechanism will position a plate on the frame D1.

The operation of the plate feed bar 54 rocks the frame guideway 34 about its pivots 38, to cause the depression of the plate-retaining tongues 15, as heretofore mentioned. The mechanism for accomplishing this is fully shown and described in my copending application, heretofore mentioned. Briefly, however, the frame guideway is provided with a cam 70, extending as shown in Fig. 10, in a direction parallel with 60 the plate feed guideway and having its right-hand end bevelled, as at 71, in Figs. 9 and 10. Pivotedly mounted to the plate-feed bar 54, is a pawl 75, which is normally maintained in contact with the bar 54, by a spring 76. When the bar 65 54 moves to the left (Fig. 9) it engages the bevelled surface 71 of the cam and raises the guideway 34 about its pivots. When, however, the bar 54 reaches its extreme left-hand position, the pawl is beyond the cam 70 and as the bar 54 moves toward the right on its return stroke, the 70 pawl is swung out of engagement with the cam 70, passing to one side thereof. Thus, the guideway 34, on the return stroke of the plate feed bar 54, remains in its lowered position, permitting the advance of the frames.

This invention is especially concerned with the method of, and apparatus for retaining the embossed plates A in stacked relationship in the magazine 32. It will be noted from Figs. 7, 9 and 10, that the right-hand end of the magazine is 5 provided with a vertically extending bar or rib 80, adapted to occupy the notch C in the right-hand end of each address plate A, as indicated in Fig. 7, and maintain the plates in stacked relationship. This bar has a cross-section preferably 10 complementary to that of the dove-tailed notch in the plate, but in any case the bar has a portion wider than the throat of the notch, so that the plate cannot be extracted horizontally from the 15 bar.

The bar 80 extends downwardly substantially into contact with the pusher 52. However, when this pusher is drawn to the right, as shown in Fig. 10, the bottommost plate A of the stack falls onto a supporting surface 81, in which position 20 it is dropped below the lowermost end of the bar 80. The plate thereabove, however, remains gripped by such bar. Hence, consequent upon the left-hand movement of the pusher 52, the bottommost plate will be ejected from the magazine 32 and the next succeeding plate will be retained therein by coaction of the bar 80 with the 25 wall of the notch C.

The left-hand end of the side of the magazine is provided with a wall 84, extending downwardly 30 as shown in Fig. 9, a distance sufficient to normally engage the left-hand edge of the second plate from the bottom in the stack. Ordinarily, as is described in my copending application, heretofore mentioned, this side wall would serve 35 to retain the second plate from the bottom in the magazine. However, I have found that sometimes address plates are provided with printing characters on their right-hand region only, as indicated by the bottommost plate A1 in Fig. 10. 40 In this instance, the second plate from the bottom A2, will be tilted, as shown, so that its left-hand edge will be in contact with the surface of the bottommost plate A1. Under these conditions, the frictional contact between the plates 45 A1 and A2 would cause the upper plate to be dragged at least part way out of the magazine by the attempted ejection of the bottommost plate. This would result in not only jamming the 50 machine but injuring both plates.

The troublesome action described is entirely avoided in my invention by the retention of the next to the bottom plate by the bar 80. By thus absolutely restricting the feed to the bottommost plate, and avoiding the discarding of an injured plate, I preserve the original order of the plates. 55

Likewise, since the bar 80 engages the right-hand notch C of the plates while the feed is toward the left, the bar need not clear the printing characters, as must the left-hand wall of the magazine. Hence, if the characters are adjacent the left-hand edge of the plate, so that the slope would be in the opposite direction to that shown in Fig. 10, the plates would be retained stacked in the magazine 32 by the bar 80. Thus, the engagement of the notches C by the bar 80 retains the plates in stacked relationship, prevents damage to the mechanism and prevents more than one plate from being fed at a time, with consequent less or disarrangement of the plates.

I have indicated at Fig. 9, a second bar 90 (which may or may not be dovetailed) secured to a left-hand wall 84 of the magazine. I have found that in some instances the width of the plates vary, making them difficult to position on 75

the frame. However, by providing the magazine with a bar 90, as well as a bar 80, I align the notches of the plate with the tongues 15 of the frames, regardless of any variation in the width of the plates. Thus, when the plates are ejected from the magazine 32 and shoved onto a frame, they will be in position proper for alignment with the tongues 15. When the bar 90 is provided, the wall 85 of the magazine may be omitted, if desired.

It is obvious, from the above description, that the retaining of the plates in their magazine by the engagement of the dovetail notch, is highly advantageous in that it prevents wedging or jamming of the plates during the feeding action. This advantage is distinct from that of maintaining the entire stack in a prearranged order. I may make the bar 80 with its dove-tailed portion only long enough to effectively engage the second plate from the bottom in the magazine.

If the bar does not extend above the topmost plate in the magazine, its upper portion should be bevelled so that the plates descending by gravity will, in effect, be speared by the bar. Indeed, with a full-height bar it is preferable to bevel the top, and as illustrated at 80a in Fig. 9, for greater convenience in manually placing the plates in the magazine.

I claim:

1. The method of preparing printing members for use comprising the steps of forming a thin plate, providing the plate with printing characters and forming a notch in one end of the plate, stacking a plurality of notched plates one above the other, and maintaining such notched plates in stacked relationship by engaging the notch of each plate.

2. The method of preparing printing members for use, comprising the steps of forming thin plates, embossing each plate to form raised printing characters thereon, forming a notch in one end of each plate, stacking a plurality of such notched embossed plates one above the other, thereafter feeding the plates successively to individual holders while retaining in the stack the plate next to the fed plate by means engaging the notch of such retained plate.

3. The method of preparing printing members for use in a printing machine, comprising the steps of forming thin plates, providing each plate with printing characters, forming a notch in one end of each plate, stacking a plurality of such notched plates one above the other, and maintaining such notched plates in stacked relationship, thereafter placing each plate on an individual holder while retaining the next adjacent plate by means engaging the notch of such plate.

4. The method of preparing printing members for use, comprising the steps of forming thin plates, providing each plate with printing characters and forming notches in opposite ends of each plate, stacking a plurality of such notched plates one above the other, and maintaining them in stacked relationship by engaging the notch of each plate, and thereafter placing each plate on an individual holder and retaining the plate in position thereon by means engaging the notches of the plate.

5. The method of preparing printing members for use in a printing machine, comprising the step of forming a plate, providing the plate with printing characters, forming a dove-tailed notch in one edge of the plate, stacking a plurality of notched plates one above the other, and thereafter plac-

ing each plate on an individual holder while retaining the adjacent plate in the stack by engaging the notch thereof.

6. The method of preparing printing members for use in a printing machine, comprising forming a dove-tailed notch in one end of a printing plate having raised printing characters thereon, stacking a plurality of plates, one above the other, thereafter removing one plate at a time from such stack while retaining the adjacent plate in the stack by means engaging the notch of such plate and positioning the removed plate on a holder.

7. The method of preparing printing members for use in a printing machine, comprising forming a dove-tailed notch in one end of a printing plate having printing characters thereon, stacking a plurality of plates, one above the other, and maintaining them in stacked relationship by simultaneously engaging the notch of each plate, thereafter removing the plates one at a time from such stack and positioning them on individual holders, and retaining the plates in position on their respective holders by engaging the notches thereof.

8. The method of preparing printing members for use in a printing machine, comprising forming a dove-tailed notch in opposite ends of a printing plate, stacking a plurality of such notched plates one above the other, thereafter removing the plates one at a time from such stack while retaining the plate next adjacent the removed plate in the stack by engaging one of the notches thereof and positioning the removed plates on individual holders, and retaining the plates in position on their respective holders by engagement of both notches of the plates.

9. The method of preparing printing members for use in a printing machine, comprising forming a dove-tailed notch in opposite ends of a printing plate having printing characters thereon, stacking a plurality of notched plates one above the other, and maintaining such notched plates in stacked relationship, thereafter feeding the plates one at a time from such stack, moving them in a direction away from one of the notches of a next adjacent plate while retaining the next adjacent plate in the stack by engaging the said notch of said plate.

10. The method of preparing printing members for use in a printing machine, comprising forming a dove-tailed notch in opposite ends of a printing plate, providing the plate with printing characters, stacking a plurality of notched plates, one above the other, and maintaining them in stacked relationship by means engaging both notches of each plate, thereafter removing the plates one at a time from such stack and positioning them on individual holders, and retaining the plates in alignment on their respective holders by engaging both notches of each plate by portions of their respective holders.

11. The method of preparing printing members for use in a series printing machine, comprising steps of forming a plurality of thin metallic elongated plates, embossing printing characters on such metal plates, punching the plates to provide them with a pair of oppositely facing aligned dove-tailed notches, stacking a plurality of frames one above the other, moving the frames one at a time from such stack to a second stack, stacking a plurality of notched plates one above the other and maintaining such notched plates in stacked relationship by engaging the rear notch on each plate with a common member, moving the notched plates one at a time forwardly in a path at right 75

5 angles to the movement of the frames to position a plate on each frame, retaining the plates in position on their respective frames by engagement of both of said notches with portions of their respective holders, and stacking the combined frames and plates.

12. In a machine for acting on plates carrying raised printing characters, the combination of a magazine in which a quantity of said plates may 10 be stacked, means to feed said plates one at a time from one end of such magazine, and retaining means engaging the plate next to the plate fed at the rear end of such engaged plate to prevent it being fed forwardly with the fed plate.

13. In a machine for acting on plates carrying raised printing characters, the combination of a magazine in which a quantity of said plates may 15 be stacked, means to feed the bottom plate from said stack, and means occupying a dove-tailed 20 notch in the rear end of the next to the bottom plate to prevent said plate being fed with the bottom plate.

14. A device for feeding printing members having dove-tailed notches at one end thereof, one 25 at a time from a stack, said feeding mechanism comprising a magazine having a member wider than the mouth of the notch and adapted to occupy the dove-tailed notch of the printing member next above the bottommost member in 30 the stack, means to engage the notched end of the bottommost printing member and move it from beneath the other members in the stack.

15. The combination of means to feed frames 35 one at a time, each frame being adapted to carry a printing member, a magazine adapted to carry a stack of printing members having dove-tailed notches in one end thereof, said magazines having means to engage the notches of the printing devices next above the bottommost device, and 40 means to eject the bottommost printing member from the magazine and position it on the frame.

16. The combination of means to feed frames 45 one at a time, each frame being adapted to carry a printing member, a magazine adapted to carry a stack of printing members having dove-tailed notches in one end thereof, said magazine having means to simultaneously engage the notches of all printing devices except the bottommost de-

vice in the magazine, and means to eject the bottommost printing members from the magazine and position it on the frame.

17. A device for feeding printing members having dove-tailed notches at one end thereof, one 5 at a time from a substantially vertically extending stack, said feeding mechanism comprising a magazine having a substantially vertically extending dove-tailed bar adapted to occupy the dove-tailed notches of all of the printing members but the bottommost member in the stack, said member being arranged to permit the devices to 10 slide downwardly in the magazine as the bottommost device is removed from the stack, means to engage the notched end of the bottommost printing member and move toward the opposite end of the stack, thereby ejecting it from the magazine, and means to prevent material downward movement of the stack until such device has been fully 15 ejected therefrom.

18. In a machine of the class described, a base, a guideway carried by the base, a magazine adjacent one end of the guideway to carry a stack of printing frames, a second guideway intersecting said first guideway, a magazine carrying a 25 stack of printing plates adjacent said second guideway, means to feed the bottom plate of said stack from the plate magazine, and means occupying a dove-tailed notch in the rear edge of the next to the bottom plate in the magazine to 30 prevent such plate being fed with the bottom plate.

19. The combination of a magazine for holding a stack of individual frames, each frame being adapted to removably support a printing member, means for feeding frames one at a time from the magazine, a second magazine adapted to carry printing members having dove-tailed notches in the ends thereof, means carried by said second magazine and adapted to engage the notches of 35 all printing devices but the bottommost device, and periodically acting means to engage the bottommost printing member and eject it from its magazine and shove it into position on the frames as they are fed from the first magazine, and 40 means to stack the combined frame and printing members.

WALTER T. GOLLWITZER.
